[57] CLAIM

The ornamental design for a filter for the recovery of embryos in animal artificial insemination processes, as shown and described.

DESCRIPTION

FIG. 1 is a top plan view of a filter for the recovery of embryos in animal artificial insemination processes showing my new design;

FIG. 2 is a side elevational view thereof, the sides opposite and adjacent being substantially similar in appearance;

FIG. 3 is a bottom plan view thereof; and,

FIG. 4 is a bottom perspective view thereof.

FIG.1

FIG.2

FIG.3

FIG.4
